UNITED STATES PATENT OFFICE.

LOUIS KOOPERSTEIN, OF NEW YORK, N. Y., ASSIGNOR TO WEST DISINFECTING COMPANY, OF NEW YORK, N. Y., A CORPORATION OF NEW YORK.

DISPENSING VALVE.

Application filed November 26, 1923. Serial No. 676,882.

To all whom it may concern:

Be it known that I, LOUIS KOOPERSTEIN, a citizen of the United States, residing in New York, county and State of New York, have invented certain new and useful Improvements in Dispensing Valves, of which the following is a full, clear, and exact specification.

This invention relates to that type of valve 10 operated by push-rod or plunger, to dispense small quantities of liquid such as soap. The object of the present invention is to provide a device of this type which is adapted to supply a measured quantity of the liquid, means 15 also being provided for ejecting the liquid under air pressure.

The invention will be understood by reference to the accompanying drawing in which—

20 Figure 1 is a longitudinal sectional elevation of an embodiment of the invention.

Figure 2 is a transverse section on the line 2—2, Fig. 1, and

Figure 3 is a side elevation of the device.

25 By reference to the drawing, it will be seen that the device comprises a casing 1 having threaded within its rear end, a plug 3, the latter being formed with a threaded 30 socket which receives the threaded end of a pipe 4 leading from the source of supply for the liquid.

Longitudinally movable within chamber 2 is a rod 4^x which is afforded a bearing surface near its inner end by plug 3, the latter being formed with a centrally disposed aperture to receive the rod. At its opposite end the rod is engaged by the headed end *a* of a push-rod *b* provided with an adjustable 40 plunger *A*. The end of casing 1 is formed with a socket which receives a packing *c* surrounding push-rod *b* and held in position by the exteriorly threaded plug *c^x*.

Liquid from the supply pipe 4 passes into 45 the axial bore 5 formed in the end of rod 4^x, and thence through port 6 into chamber 2.

Casing 1 is formed with a hollow dome-like boss 7 which, at its upper end, is reduced in diameter to provide an annular shoulder 7^x, the boss above said shoulder being threaded to receive a cap 8, the latter serving to hold in position a disk 9 which may bear the name of the manufacturer or any other

desired wording. When the parts are in 55 their normal position, as illustrated in Fig. 2, the interior of boss 7 affords a reservoir which is in communication with the supply pipe 4, the liquid flowing from chamber 2 into the reservoir.

The device is provided with a discharge nozzle 10 which communicates with a chamber 11 formed within the casing 1, this chamber being of relatively small diameter, so that a seat 12 is provided intermediate the 65 two chambers against which seat a valve disk 13 may rest, thus shutting off chamber 11 and discharge nozzle 10 from chamber 2 and the reservoir. Valve disk 13 is normally maintained in closed position by means 70 of a helical spring 14, one end of the spring engaging plug 3 and the opposite end engaging the disk the latter being formed with a flanged head.

It will be seen by reference to Fig. 1 that 75 rod *b* projects through valve disk 13. To prevent the passage of liquid from chamber 2 intermediate the rod 4 and the disk, the rod is provided with a packing 15; and a packing ring 16 is carried by the flanged 80 head of valve disk 13.

In the operation of the device, depression of plunger *A* will impart an endwise movement to rod 4^x against the action of a helical spring 18, one end of the said spring engaging a head 19 on rod 4^x, the opposite end of the spring engaging block 3. In its movement, rod 4^x carries port 6 beyond chamber 2 so that communication between the latter and supply pipe 4 is shut off. Upon continued movement of the plunger *A*, its collar *b^x* will engage valve disk 13 and will move the same against the action of spring 14, to open connection between the reservoir and discharge nozzle 10. Therefore, 85 the liquid within the reservoir will be discharged under the pressure of air contained in the top of the reservoir. The said air flows downwardly with the liquid from the supply tank and passes, of course, to the point of highest elevation, i. e., to top of the reservoir. By varying the size of the reservoir, any desired quantity of liquid 90 may be discharged from the device by a single movement of the push-rod *b*.

100 It will be seen that prior to the opening of the discharge nozzle 10 the main supply of the liquid will be shut off from the device,

- due to the closing of port 6, so that the pressure under which the liquid is forced through nozzle 10 is introduced by the air trapped in the top of the dome-like reservoir, and the compressive action of the valve disk 13 in its movement inwardly, inasmuch as the disk has a substantial inward movement before communication is effected between the discharge nozzle and the liquid.
- 10 Assuming the parts to be in the position illustrated in Fig. 1, but empty of the liquid, it will be seen that the device affords a trap for air inasmuch as the discharge outlet is closed by disk 13. Now when the liquid 15 under pressure enters the device through port 6, the air will be displaced by liquid and will be forced under pressure to the top of the dome-like reservoir, this pressure being equal to the pressure upon the liquid.
- 20 When port 6 is closed by operation of the plunger and discharge outlet is opened by movement of the disk 13, the air under pressure in the top of the reservoir will exert a positive ejecting force upon the liquid so 25 that the latter will be expelled from the

device through the discharge outlet, as will be understood without further explanation.

Having described my invention what I claim and desire to secure by Letters Patent is as follows:—

30 In a dispensing device, in combination, a casing formed with a chamber extending longitudinally therein and a second chamber closed at its upper end and extending transversely of the first chamber in communication with the latter, and a valve device for controlling the admission to and the discharge of liquid from the casing, the liquid being permitted to flow to the second chamber via the first chamber whereby air 35 is trapped in said second chamber above the liquid, for the purpose described.

35 In testimony whereof, I have signed my name to this specification in the presence of two subscribing witnesses.

LOUIS KOOPERSTEIN.
